UNITED STATES PATENT OFFICE.

HARDY CROOM, OF SAVANNAH, GEORGIA.

TICKET-HOLDING DEVICE.

Application filed January 10, 1925. Serial No. 1,713.

This invention relates to transfer tickets and the like and has for its object the provision of a device adapted to hold a pad of such tickets adjustably in position to present a part of a ticket for separation from the body of the ticket along a selected line of severance, which severance line may be varied from time to time, for the purpose of indicating the approximate time of issue of the ticket.

Fig. 1 is a plan view of the invention with a pad of transfer tickets disposed therein.

Fig. 2 is a side view of Fig. 1.

Fig. 3 is a plan view of the detached portion of the transfer ticket.

A transfer ticket adapted for use in connection with this invention comprises a rectangular paper strip 10 having a plurality of transversely-printed rows of figures 12, of which a selected one of the figures is adapted to indicate the approximate time of issue of the transfer ticket. The device embodying this invention is arranged to support a pad of such strips in such a manner that a portion of the strip may be detached from the body of the strip along such a line of severance that the last figure on the detached portion 10^a indicates approximately the time of issue of the transfer ticket.

The ticket-holding device embodying the invention includes a relatively flat rectangular supporting plate 14 which may be formed or provided with screw-receiving apertures 16 by which the device may be attached to a suitable support. The front face of said plate may be formed or provided with a plurality of transversely-disposed teeth 18 located adjacent one of the narrower edges of the plate, whereby to aid in holding a pad of transfer tickets firmly on the front face of the plate.

A holding frame is associated with said plate and is adapted to bear against the top face of the ticket-pad. Said frame includes a plate 20 disposed above the supporting plate and provided with a pair of parallel and integrally-formed arms 22 which depend over and extend along the opposite sides of the supporting plate. The ends of said arms are integral with a pressure bar 24^a which is disposed transversely above said supporting plate. Said holding frame is hingedly-connected with the supporting plate by means including two spaced arms 26, which arms extend rearwardly from said plate 20 in approximately parallel

relation and through slots 28 formed in said supporting plate. Said arms 26 are fixed to the ends of a hinge-shaft 30, which shaft is disposed within a housing 32 carried by the rear face of the supporting plate. A spring 34 is disposed within said housing and is connected with said housing and said shaft in such a manner as to exert a pressure on said holding frame in a direction to move it toward the supporting plate.

A pad of transfer tickets 10 is adapted to be disposed between the supporting plate and the holding frame; and the holding frame is provided with means by which a portion of a ticket may be severed from the body thereof in such a way that any selected time-figure 12 on the ticket may be the last figure on the ticket. The ticket-severing means comprises a knife-blade 36, which knife blade is secured on the lower face of and is approximately co-extensive with the pressure-bar 24 of the holding frame and may be fixed in such position in any suitable manner, as by the rivets 38. Said knife-blade is formed with two stepped and approximately parallel cutting edges 40 and 42 and the diagonally-disposed and connecting cutting edge 44. The cutting edge 42 is shorter than the cutting edge 40 and is spaced ahead of said cutting edge by a distance about equal to the spacing of the rows of time-figures 12 on the transfer ticket.

When a transfer ticket is to be issued with one of the intermediate time-figures of a row as the last figure on the ticket as, for instance, the figure 4:30, the ticket is disposed beneath the knife blade in a manner as to position the long cutting edge 40 beneath the transverse row including this figure and the diagonal cutting edge immediately after this figure; and the ticket will be severed along the line of cutting edges as illustrated in Fig. 3, where 46 represents the line of severance.

The cutting edge 40 is adapted to have a length sufficient to extend entirely across the transfer ticket, so that the last figure in a line of time-figures may be included in the severed ticket; and the cutting edge 42 is adapted to have a length sufficient to extend entirely across the ticket from between the first and second figures of a row, so that the ticket may be severed to bear, as its last figure, any figure in a row of figures.

The side arms 22 of the holding frame may be formed or provided with opposed

struck-out projections, or finger-grips, 48, by which the holding frame may be grasped and raised to release the pad of tickets.

I claim:

1. A ticket holding device comprising a supporting plate for a ticket, a holding frame disposed above said plate and hinged-ly-connected therewith at one end, a knife blade carried by said frame transversely above said plate and having two stepped cutting edges and an intermediate diagonal connecting cutting edge, one or all of which cutting edges are disposed to act upon a ticket disposed therebeneath, said plate having a plurality of teeth in that portion disposed beneath said knife blade, and yielding means urging said frame and knife blade toward said plate.
2. A ticket holding device comprising a supporting plate for a ticket, a holding frame disposed above said plate and including a plate having a hinged-connection with said supporting plate at one end, said frame including a pair of arms integral with said frame-plate and extended in parallel relation along the opposite side edges of said supporting plate, a bar disposed transversely above said supporting plate and integral with said arms, a knife-blade carried by the lower face of said bar, said knife-blade having two stepped and approximately parallel cutting edges and an intermediate diagonal connecting cutting edge, and yielding means urging said frame and knife blade toward said supporting plate.
3. A ticket holding device comprising a flat supporting plate formed with a pair of spaced slots in one end thereof, a spring-hinge member carried by the rear face of said supporting plate between said slots, a holding frame disposed above said supporting frame and including a frame-plate having two integral arms which are extended rearwardly and through said slots in said supporting plate and have connection with said spring-hinge member, said frame-plate having a pair of integral spaced parallel arms which depend over and extend along

the opposite side edges of said supporting plate and a connecting bar integral with said arms and disposed transversely above said supporting plate, and a knife blade carried by the lower face of said connecting bar, said knife blade having two approximately parallel and stepped cutting edges and an intermediate diagonal connecting cutting edge, all of which cutting edges are adapted to be disposed for operative relation with a ticket carried by said supporting plate beneath said knife-blade.

4. A ticket holding device comprising a flat supporting plate formed with a pair of spaced slots in one end thereof, a spring-hinge member carried by the rear face of said supporting plate between said slots, a holding frame disposed above said supporting frame and including a frame-plate having two integral arms which are extended rearwardly and through said slots in said supporting plate and have connection with said spring-hinge member, said frame-plate having a pair of integral spaced parallel arms which depend over and extend along the opposite side edges of said supporting plate and a connecting bar integral with said arms and disposed transversely above said supporting plate, and a knife blade carried by the lower face of said connecting bar, said knife blade having two approximately parallel and stepped cutting edges and an intermediate diagonal connecting cutting edge, all of which cutting edges are adapted to be disposed for operative relation with a ticket carried by said supporting plate beneath said knife-blade.

In testimony whereof, I have signed my name to this specification.

HARDY CROOM.
